UNITED STATES PATENT OFFICE.

LOUIS A. NEGRAVAL, OF JERSEY CITY, NEW JERSEY, ASSIGNOR TO HENRY C. FRANK AND HENRY GUTMANN, OF NEW YORK, N. Y.

CUFF-FASTENER.

SPECIFICATION forming part of Letters Patent No. 445,512, dated January 27, 1891.

Application filed November 7, 1890. Serial No. 370,602. (No model.)

To all whom it may concern.

Be it known that I, LOUIS A. NEGRAVAL, a citizen of the United States, residing in Jersey City, in the county of Hudson, in the State 5 of New Jersey, have invented a certain new and useful Improvement in Cuff-Fasteners, of which the following is a specification.

The difficulties attending the securing of cuffs to shirt-sleeves by the ordinary button 10 are so great that many efforts have been made to provide a more conveniently-operated and more efficient fastener. My invention is an improvement in this direction. It is gentle in its action on the cuff, is easily inserted, is 15 reliably held, and is easily removed when desired. I employ any ordinary or suitable means of connecting the fastener to the shirt-sleeve, preferably by a clamp engaging the sleeve by the edge of the slit near the wrist- 20 band. Such allows the fastener to be shifted up and down, and consequently the cuff to be more or less exposed beyond the coat-sleeve, as the taste or convenience of the wearer may dictate. A strip of flat metal, which may be 25 German silver or any suitable metal, cut by a die to the required form and smoothly finished, extends from the clasp a little distance along the sleeve, then bends abruptly at a right angle and extends upward from the wrist 30 a little distance, and then again bends abruptly, extending along a little farther in a direction parallel to the main body and to the wrist of the wearer. The end is smoothly rounded. The offset formed by the two abrupt 35 bends should be sufficient to allow for the two thicknesses of the cuff and a little excess, which excess allows for a slide, which performs important functions in locking and unlocking.

40 The accompanying drawings form a part of this specification and represent what I consider the best means of carrying out the invention.

Figure 1 is a perspective view showing the 45 fastener in use. Figs. 2, 3, and 4 show the fastener detached. Fig. 2 is a face view. Fig. 3 is an edge view, and Fig. 4 is a longitudinal section. Fig. 5 is a section corresponding to Fig. 4, but showing the fastener engaged or 50 locked, holding the cuff. The two thicknesses of the cuff are shown in section. Fig. 6 is a

face view corresponding to Fig. 2, but showing a modification.

Similar letters of reference indicate corresponding parts in all the figures where they 55 appear.

A is the body, A' the offset, and A² the extension beyond the offset, which when the device is in use is thrust through the button-holes and lies parallel with and close along 60 the inner face of the cuff. A hole a is formed in the offset of proper form to allow the movement of a flat slide.

B is the slide, having a rounded end and extending along the inner face of the body A 65 and through the aperture a. When it is thrust forward, its end extends beyond the offset A' and lies on the outer face of the cuff-body opposite to the extension A² of the main body. The rear end of the slide is bent at 70 right angles to form a handle or catch by which the slide may be easily drawn back, as required, for attaching and detaching a cuff. The slide is further guided by lips A³ A³, formed on the edges of the body. 75

The rear end of the body A is formed into a pivot A⁴, on which is swiveled a clasp M, which is equipped with a spring and is capable of taking hold with sufficient force on the shirt and holding the fastener and the attached cuff 80 reliably, as has been long practiced with other forms of fasteners.

To insert my fastener, the slide B being drawn back so as to not extend but little, if at all, beyond the offset A', the point A² is inserted in the button-holes of the cuff, thrusting it from the interior outward, and when fully thrust out, so that the offset bears against the interior of the cuff, the device is turned to extend the offset up through the button-holes and bring the point or rounded end parallel to the part A², embracing the two thicknesses of the cuff between itself and the said part A². This locks the device firmly. It cannot be unlocked by any movement of the fastener until the slide B has been drawn 90 back. When it is desired to disengage the fastener, the wearer touches the handle B', 95

and pressing backward thereon with sufficient force moves the slide to the extreme backward position which it occupied at first. Now, the device can be easily disengaged by the reverse movement to that by which it was inserted.

The limit of the backward movement of the slide may be determined by the handle B' striking the clasp M. The position of the extreme backward motion should be accurately determined. It should be such that the point will lie in or very slightly protruding beyond the offset A'. In the forward or outward movement of the slide it is not material at what precise point it comes to rest. I avail myself of this fact to insure a high degree of friction to aid in holding it in its extreme outward position. This is effected by making the body of slide B very slightly tapered and forming the body A, or rather the space within the lips A³, correspondingly tapered, the taper being such that the slide when it has been thrust forward to about the right position is arrested by wedging within the lips. Care being taken by suitable dies or otherwise to make the taper of each very moderate, the frictional force with which the slide may be held is very great. In moving the slide backward or forward it moves easily in all parts of the motion, except while near the outward position, when it is subject to the extreme friction.

With the exception of the long-approved clasp M, there are no working parts, except the simple straight slide above described working between the lips and extending through the hole in the body.

The device is strong, easily worked, and holds reliably. It does not abrade the button-holes or expose them to any serious wear, either while in use or while being inserted or removed.

Modifications may be made without departing from the principle or sacrificing the advantages of the invention. Instead of the continuous lips A³, one or more short narrow wings may be formed on the edge of the body,

and properly bent over like the lips A³. In such case a pair of such narrow wings may be formed on the body near the offset A, ready to guide the slide if, through any accident or malformation, the slide should be drawn quite out through the hole a, and the rear end of the slide may be provided with a pair of corresponding narrow wings, which may be bent backward and engage around the edge of the body. Fig. 6 shows such a modification. I prefer the form first shown.

I claim as my invention—

1. In a cuff-fastener, the body A, having an offset A' and point or extension A², substantially parallel with the part A, adapted to be thrust partially through the button-holes of a cuff and having a clasp M on the rear end, in combination with a slide B and suitable guiding means therefor, adapted when thrust forward to present its point parallel with the point upon the opposite side of the cuff, and thus firmly lock the device to the cuff while the clasp holds the device to the shirt-sleeve, all substantially as herein specified.

2. In a cuff-fastener, the body A, with offset A', having hole a, point A², lips A³, and pivot A⁴, in combination with the clasp M and with the slide B, guided within the lips A³ and playing through the hole a and having an operating catch or handle B', all arranged to serve substantially as herein specified.

3. The slide B, formed tapering, as described, in combination with the body A, having the hole a, and lips A³, adapted to arrest the slide by friction at the outward extreme of its movement, and having the offset A', point A², and clasp M, all arranged for joint operation relatively to each other and to a cuff and sleeve, substantially as herein specified.

In testimony that I claim the invention above set forth I affix my signature in presence of two witnesses.

LOUIS A. NEGRAVAL.
